Atty.

UNITED STATES PATENT OFFICE.

LESLIE H. BURLIN, OF CHICAGO, ILLINOIS, ASSIGNOR TO CHICAGO HARDWARE FOUNDRY COMPANY, OF NORTH CHICAGO, ILLINOIS, A CORPORATION OF ILLINOIS.

AQUARIUM.

Application filed June 26, 1926. Serial No. 118,755.

This invention relates to household aquaria-
5 mums of the drum or barrel type, in which
the annular shell or body member receives
and holds in a water tight manner the flat
transparent heads or end members in parallel
10 and separated relation. And the present im-
provement has for its object:—

To provide a structural formation and as-
sociation of parts of the annular plate metal
15 body of an aquarium, whereby the flat and
transparent end heads or members are re-
ceived and secured in place in a water tight
condition and in a ready and substantial
manner, all as will hereinafter more fully
20 appear.

In the accompanying drawing:

Fig. 1 is an elevation of an aquarium of
the drum type, embodying the present in-
vention.

20 Fig. 2 is a top plan of the same.

Fig. 3 is a detail transverse section on line
3—3, Fig. 2.

Fig. 4 is a detail longitudinal section on
line 4—4, Fig. 2.

25 Like reference numerals indicate like
parts in the different views.

The annular shell or body member 1 of the
aquarium is formed as a split ring of plate
30 metal, with each of its ends formed with an
annular receiving channel for the reception
of the marginal portion of one of the trans-
parent end heads or members 2 of the aqua-
rium, and with each of such channels formed
35 by a split bead formation comprising a split
out turned annular web 3, a like split annular
intermediate web 4, and a like split in-
turned web 5, with such parts integrally
formed on the respective ends of the annular
40 shell or body member 1, by the usual
metal rolling or beading operations.

The receiving channels formed as above
described, are of a size a degree larger than
the size of the marginal portions of the
transparent heads 2 which they are intended
45 to receive, and so that an intermediate filling
6 of elastic packing or composition can be
used as a setting for the heads 2 in the at-
tainment of an effective water tight joint be-
tween the parts or elements.

50 In the described construction the annular
split shell 1 is initially expanded or spread
to the required diameter, to permit the in-
troduction of the transparent heads 2 into
aligned relation with the channels of said
55 shell, after which the shell is allowed to con-

tract and engage the margins of the trans-
parent heads 2 in the receiving channels
aforesaid.

In such assemblage of parts, the elastic
packing 6, may be in place during the above
described assembly operation, or subse-
quently applied as found most desirable by the
manufacturer. In this connection a material
feature of the invention involves means for
securing the split shell or body member 1 in
its proper contracted condition upon the
transparent end heads 2. In the construc-
tion shown, such means comprises a coupling
plate 7 spanning the split or parting in the
split shell 1 and secured to said shell ad-
jacent to said split by screw bolts 8 passing
through orifices in both parts, with the ori-
fice in one part adapted to register with its
complementary orifice in the other part
when the annular shell or body member 1, 75
is in its properly contracted condition.

In this improvement the coupling plate 7
is formed with an orifice 9 to constitute the
entry passage to the interior of the aqua-
rium and to such end is of an open and 80
preferably approximately elliptical ring
form as shown, having any desired orna-
mental configuration, with its respective
ends formed with pivot eyes 10 for the at-
tachment of loop shaped rings or handles 85
11 for convenient handling of the aquarium.

Having thus fully described my invention
what I claim and desire to secure by Letters
Patent is:—

1. An aquarium comprising in combina-
tion, an annular split shell of plate metal
formed with receiving channels at its respec-
tive ends, end walls of transparent material
having marginal engagement in said chan-
nels, and means for securing the split shell 90
in a contracted condition on said end walls,
the same comprising a coupling plate span-
ning the split of the split shell and secured
to the adjacent ends thereof by screw bolts,
said coupling plate having an orifice con-
stituting the entry passage to the aquarium
chamber.

2. An aquarium comprising in combina-
tion, an annular split shell of plate metal
formed with receiving channels at its re-
spective ends, end walls of transparent ma-
terial having marginal engagement in said
channels, and means for securing the split
shell in a contracted condition on said end
walls, the same comprising a coupling plate 105
110

of an open center and approximately elliptical form spanning the adjacent ends of the split shell with the parts secured together by screw bolts, the open center of the coupling plate constituting an entry passage to the aquarium chamber.

3. An aquarium comprising in combination, an annular split shell of plate metal formed with receiving channels at its respective ends, end walls of transparent material having marginal engagement in said channels, and means for securing the split shell in a contracted condition on said end walls,

the same comprising a coupling plate of an open center and approximately elliptical form spanning the adjacent ends of the split shell with the parts secured together by screw bolts, the open center of the coupling plate constituting an entry passage to the aquarium chamber, said coupling piece having pivot ears at its opposite ends for the reception of loop shaped handles for the convenient handling of the aquarium. 15 20

Signed at Chicago, Illinois, this 24th day of June, 1926.

LESLIE H. BURLIN.
